COMB CLEANER

Shirley True, Los Angeles, Calif.

Application April 24, 1936, Serial No. 76,246

4 Claims. (Cl. 15—142)

The present invention relates to improvements in comb cleaners.

It is one of the important objects of the invention to provide in a device of the above character one which is particularly adapted for efficiently removing from the roots of the comb's teeth foreign matter such as dandruff or other scaly impurities which, if allowed to remain in the comb, are likely to spread germ disease to whom-
10 ever might use the comb.

It is also an important object of the invention to provide a device of the character specified which will be sanitary and one which after use can be easily cleaned and sterilized without the necessity of providing any special tool or device for the purpose.

It is a further important object of the invention to provide a comb cleaner which is simpler, cheaper, and more easy to manufacture.

Still another object of the invention is to provide an important step in the manufacture of the article wherein is employed a jig having a plurality of spaced holes for holding the cleaning teeth in an assembled relation incident to forming a support or handle means for them.

Yet another important object of the invention is to provide a plurality of particular pointed teeth which when assembled may occupy the same position in the jig or a disarranged position therein whereby after the handle is applied to the teeth and the article is removed from its mold the cutting edges of the teeth will occupy the same cutting plane or different planes, the idea being to have no two teeth occupying the same position in the handle in order to separate the refuse from the roots of the comb more efficiently as the cleaner is applied first to one side of the comb and then the other, since the material may be more dense between some teeth than the others and more irregularly compacted therein.

Still other objects, features and advantages of the invention remain yet to be listed, some of which will be obvious to the skilled technician in the light of the following disclosure and the drawing pertaining thereto.

Referring to said drawing:

Fig. 1 is a perspective view of the device per se.

Fig. 2 is a plan view of a female mold containing a jig with the teeth of the cleaner mounted therein ready for molding the handle around them.

Fig. 3 is a longitudinal mid-section taken thru the view shown in Fig. 2, with a fragmentary portion of a male mold slightly projected into the female mold.

Fig. 4 is an enlarged fragmentary perspective view of a modification of the scored teeth of the cleaner.

Referring in detail to the drawing, the die structure shown includes a female mold member 1, desirably shaped as a rectangular block, comprising a body portion provided with a recess 2 within which is removably fitted the jig block 4 whereby the bristles or teeth 3 of the cleaning implement are shown supported in their proper 10 relative positions preparatory to having the handle 6 molded around them. A plurality of dowel pins 5 are shown to aid in keeping the block 4 properly positioned upon the mold member 1.

With the female member 1 of the mold cooperates a male mold member 7 having a molding extension 8 which is T-shaped in transverse section and which is thus adapted to cooperate with a T-shaped cavity which is afforded in the female mold member, in conjunction with the inserted block 4, by an elongated recess 9 having an expanded end portion 10.

The cleaner's teeth 3 are shown as small semi-flexible rods made from spring steel, piano wire or the like, each of which has a slight kink, curve or deflection 14 therein near one end. These teeth are supportable by the jig 4 in a spaced parallel relation to each other in substantially the same plane, with their end portions that are furnished with the deflected portions 14 projecting horizontally into the recess 10 which is provided to aid in molding the head 15 with which the handle 6 is furnished. 11x and 12x designate the handle-molding recess portions in the male mold member which align respectively with the recesses 11 and 12 of the female mold member.

Each of the cleaner teeth or bristles 3 in the modification in Fig. 4 is shown furnished with a plurality of indentations or scorings 15a to cause them to be more efficient in the removal of dandruff and other foreign matter from combs or brushes. Said scorings 15a of each tooth are located on opposite sides thereof, the scorings on one side being in a staggered relation to those on the opposite side of the tooth in order not unduly to weaken the same. Each tooth 3a is also shown having a 45 degree bevel 16 at its outer end to adapt it more readily to cut its way through obstructions which it will need to penetrate.

In carrying out the invention as a method for making comb cleaners, before the jig block 4 is inserted into the female mold member the bristles or pins 3 or 3a are inserted therein into the small bores provided for them in said block, said

bore being of the proper depth to cause the projecting end portions of the pins, when fully inserted, to aline as shown in Figs. 2 and 3.

It is not necessary that the deflections 14 of the assembled pins be all directed downwardly as shown in Fig. 3, and preferably said pins are inserted with the bevels at their ends in various rotational positions in order that by a repeated insertion of the cleaner into the opposite sides 10 of a comb a more efficient cleaning may result.

After said pins have been assembled therein said jig block is put into place as shown in Fig. 3. Thereupon the molding around the kinked pin portions of the head 15 of the handle 6 is per- 15 formed in a well known manner, by heating the mold members and pressing them together after a measured predetermined amount of the handle-forming material has been placed within the mold cavity of the female mold member.

20 It should be understood that the present disclosure is for the purpose of illustration only and that this invention includes all modifications and equivalents which fall within the scope of the subject matter claimed.

25 What is claimed is:

1. A comb cleaner comprising a row of teeth consisting of rods which are furnished with a multiplicity of laterally spaced scorings comprising V-shaped notches located in only two opposite sides of each rod, the scorings on one side being in a staggered relation to those on the 30

opposite side of the tooth, said rods being ar- ranged so that the notches in adjacent rods face each other and a handle member for said teeth.

2. In a comb cleaner, a handle member having a head, a multiplicity of rod-like teeth secured to 5 said head, said teeth being substantially parallel to each other, equally spaced in a single row, and occupying substantially the same plane, the end surface of each tooth occupying an inclined plane to produce a chisel edge at one side of the tooth, 10 the inclined end surfaces of the different teeth occupying various non-parallel planes and ex- tends outwardly in different directions.

3. In a comb cleaner, a handle member having a head, and a multiplicity of semi-flexible rods 15 each provided with a kink adjacent an end thereof and those ends being fastened indiscriminately within said head, said rods outside said head being substantially parallel to each other and arranged singly in a row occupying substantially the same 20 plane, said kinks being individually embedded on all sides within the material of said head.

4. A comb cleaner comprising a set of rod-like teeth which are individually furnished with lat- 25 eral scorings comprising notches located in only two opposite sides, the scorings on one side being in a staggered relation to those on the opposite side of the individual tooth, and a handle member for said teeth supporting their scored portions facing each other. 30

SHIRLEY TRUE.
